CLAIM

The ornamental design for a cradle for electric toothbrush, as shown and described.

DESCRIPTION

FIG. 1 is a perspective view of a cradle for electric toothbrush showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an exploded figure, showing the cradle for electric toothbrush aligned with its corresponding toothbrush and toothbrush case.

The element shown in broken lines in the drawing figures illustrate environmental structure and form no part of the claimed design.
